MOP WRINGING DEVICE

Edward Pavek, Minneapolis, Minn.

Original application February 23, 1933, Serial No. 657,956. Divided and this application March 23, 1936, Serial No. 70,518

28 Claims. (Cl. 15—261)

This invention relates to a mop wringing apparatus and while the apparatus is capable of being secured to a pail and mounted on a pail in various ways, it particularly is illustrated as a device having means supporting it upon the edge of the pail and being readily removable from the pail.

It is an object of this invention to provide a mop wringing apparatus comprising a frame adapted to be supported on or in a pail, said frame having a pair of plates mounted therein adapted to be moved toward each other to squeeze a mop therebetween, together with means including a toggle construction for moving said members together with increasing leverage as said members approach each other.

It is a further object of the invention to provide a mop wringing apparatus comprising a frame, a pair of plates carried in said frame, a lever arm pivotally connected to one of said plates extending upwardly and adapted to be operated by the stick of a mop to be squeezed together with a member pivotally connected to said lever arm and frame and forming with said lever arm a toggle.

It is still another object of the invention to provide a mop wringing apparatus comprising a pair of plates movable toward and from each other and diverging upwardly when in separated position, together with a bottom plate carried by one of said plates and movable through the other of said plates when said plates approach each other, means preferably being provided to secure said bottom plate in different positions or at different heights.

It is also an object of the invention to provide a mop wringing apparatus comprising a frame, a pair of plates mounted therein for relative movement toward and from each other to squeeze a mop therebetween and diverging upwardly when in separated position, one of said plates having an adjustable portion adapted to be held in various positions to vary the position of the upper edge of said plate.

It is still further an object of the invention to provide a mop wringing apparatus comprising a frame, a pair of plates mounted therein for relative movement toward each other, a lever arm extending upwardly for moving said plates toward each other, together with novel means carried by the stick of a mop to be squeezed engageable with said lever arm.

These and other objects and advantages of the invention will be fully set forth in the following description made in connection with the ac-

companying drawings, in which like reference characters refer to similar parts throughout the several views and in which:—

Fig. 1 is a view in side elevation of said apparatus disposed in a pail, which pail is shown in vertical section;

Fig. 2 is a vertical section taken on line 2—2 of Fig. 4 as indicated by the arrows, the plates being shown in separated position;

Fig. 3 is a view similar to Fig. 2 showing the plates in mop-squeezing position with a mop therebetween and showing the operating lever arm;

Fig. 4 is a top plan view of the apparatus and a portion of the pail;

Fig. 5 is a view in side elevation of the operating lever arm and engaging member with a portion of the mop stick;

Fig. 6 is a top plan view of Fig. 5;

Fig. 7 is a vertical section taken on line 7—7 of Fig. 5 as indicated by the arrows;

Fig. 8 is a view similar to Fig. 3 shown without the pail and showing a modification;

Fig. 9 is a view as seen from the right of Fig. 8;

Fig. 10 is a horizontal section taken on line 10—10 of Fig. 8 as indicated by the arrows;

Fig. 11 is a vertical section taken on line 11—11 of Fig. 13 as indicated by the arrows;

Fig. 12 is a partial view similar to Fig. 3, showing the parts in mop-squeezing position;

Fig. 13 is a top plan view of Fig. 12;

Fig. 14 is a partial view similar to Fig. 11, shown on an enlarged scale;

Fig. 15 is a section taken on line 15—15 of Fig. 14;

Fig. 16 is a section taken on line 16—16 of Fig. 13, as indicated by the arrows;

Fig. 17 is a view in side elevation of a lever construction and mop stick used therewith; and

Fig. 18 is a vertical section taken on line 18—18 of Fig. 17.

Referring to the drawings, particularly Figs. 1 to 4, a pail 20 is shown adapted to contain wash water, the same having a vertical wall or partition 20a. While pail 20 could be of various forms, in the embodiment of the invention illustrated it is shown as rectangular in plan. A frame member 21 is shown comprising parallel vertical plates 21a each having a slot 21b adjacent one side in which the upper portion of wall or partition 20a is disposed so that said frame is supported on said wall or partition. Plates 21 have their sides converging toward their lower ends and the same are provided with projections 21c at their bottoms vertically aligned with slot 21b and adapted

15

35

30

40

50

55

to engage the side of wall or partition 20a. Said plates at one side and at some distance from the top are connected by a transverse plate 22 which extends along one edge of plates 21 and then extends substantially horizontally across plates 21a. 5 Plates 21 and 22 are provided with a plurality of drain holes 21f. Plates 21a adjacent said edge and above plate 22 are provided with a plurality of holes 21d through any alined pair of which 10 a headed rod 23 may be passed to extend between said plates. A plate 24, forming in effect a portion of plate 22, has its upper end bent into cylindrical form and adapted to have rod 23 pass therethrough so that it is supported on said rod 15 and extends downwardly along the inner side of plate 22. Plate 24 can thus be supported at different heights and its upper edge will be disposed at different heights. Plates 21a each have an 20 arcuate slot 21e in their upper portions, which slot is concentric with the center of pivot rivets or bolts 25 in the lower part of said plates. Links or arms 26 are secured at their lower ends to pivots 25 respectively and extend upwardly inside of and closely adjacent plates 21a, the same 25 passing between the sides of the horizontal portion of plate 22 and plates 21a. Arms 26 are connected by pivot members 27, which may be bolts or rivets, to lever arms 28, said pivot members 27 passing through the slots 21e and levers 28 30 being disposed at the outer sides of plates 21a. Arms 26 have secured thereto along their sides adjacent plate 22 a flat plate 29 which extends from adjacent the horizontal portion of plate 22 upwardly and has its upper end curved rearwardly over the upper ends of arms 26. Lever 35 arms 28 as shown in Fig. 4 are bent to extend toward each other and are then bent to have portions 28a extending in spaced parallel relation. Another arm 30 is disposed between portions 28a, 40 being pivotally connected to the same adjacent its lower end by a pivot rivet 31 having thin washers thereon at either side of arm 30. Arm 30 and portions 28a have a plurality of alined holes 30a through one set of which extends a 45 wooden pin 32. Lever 30 and portions 28a are thus connected for simultaneous movement. The upper end of arm 30 is provided in one edge with a plurality of spaced recesses 30b. In Fig. 3 a mop 33 is shown carried at the lower end of a 50 handle or mop stick 34. A member 35 is adapted to be secured to mop stick 34 and the same has at its sides flat narrow projections 35b rectangular in cross section and adapted to be received in the recesses 30b. Member 35 comprises a 55 pair of oppositely formed strips or short bars 35a having central portions adapted to embrace mop stick 34 and having engaging portions at one side thereof connected by a rivet 35c. At the other side of mop stick 34 portions 35a are separated and connected by a headed stud 35d having thereon a wing nut 35e, portions 35a being somewhat resilient. Member 35 can thus be 60 loosened by means of nut 35e moved along stick 34 as desired and clamped in the desired position 65 thereon. The other ends of levers 28 are provided with a plurality of spaced holes 28b through any one of which a stud 36 may pass having its head countersunk into said lever. Short bars 37 are secured to the outer sides of 70 plates 21a adjacent one side thereof and the same are provided with a plurality of spaced holes 37a. The holes 28b and 37a can be brought into alinement in pairs and studs 36 extend through one of the alined pairs, said studs being 75 provided with wing nuts 38. It will be seen

that levers 28 together with members 37 form a toggle lever and that this toggle lever may be varied by positioning stud 36 in different pairs of said holes so that plate 29 will be nearer to or farther from plate 22 when the toggle is straightened.

In Figs. 8 to 9 a modification is shown in which a plate 40 is used instead of plates 22 and 24. Plate 40 extends between and connects plates 41 which are quite similar to plates 21a already described. Plate 40 has several transverse slots 40a formed therein, the metal from said slots being turned outwardly and downwardly. Plate 42 which is similar to plate 29 has transversely alined and vertically spaced pairs 15 of slots 42a therein, which pairs are substantially alined vertically with the slots 40a. A plate 43 is provided forming a bottom plate and the same has lugs 43a adapted to extend through a pair of the slots 42a. A bail rod 44 has its 20 ends bent at right angles and adapted to extend through holes 43b in the lugs 43a, said bail being disposed at the opposite side of plate 42 from the main portion of plate 43. Plate 43 is thus detachably connected to plate 42 and may be 25 connected to plate 42 at different heights. Plate 43 extends through one of the slots 40a as shown and moves through said slot when plates 40 and 42 are relatively moved. Plate 42 is carried by arms 45 pivoted to pivots 46 in the bottom of 30 plates 41. Plates 41 have slots 41a similar to slots 21b and have the lower projections 41b similar to projections 21c. Plates 41 also have inwardly projecting short lugs 41c to which are fastened one end of springs 47, the other ends 35 being fastened to studs 48 on arms 45. Springs 47 are so arranged that plate 42 will normally be held in its position separated from plate 40 and said springs will be extended when plate 42 is moved toward plate 40. Springs 47 may also 40 be compressed by moving plate 42 to its rearward limit of movement. Lever members 28 and 37 are provided as already described. Plate 43 is provided with a plurality of drain slots 43c. A bar 50 is secured to levers 28 in the same 45 manner that bar 30 is secured and extends upwardly from levers 28. Bar 50 has secured to its upper end by a rivet 51 and extending at right angles therefrom a bar 52, the same having its end bent into substantially semi-circular form. A piece of flexible tough material 53 such as leather is secured at one side of bar 52 by a rivet 54, said piece extending around the end of said bar and into the bight thereof and having its other end secured to the opposite side 55 of bar 52 by rivet 54. The mop stick 34 is adapted to be received in the fold or bight of the material 53 as shown in Figs. 17 and 18.

In operation of the structure shown in Figs. 1 to 7, the device will be placed in the pail as shown, 60 which pail will contain the wash water. Plate 24 will be adjusted as desired by placement of rod 23 in the desired pair of holes 21d. If a heavy or large mop is being used said plate will be at one of its upper positions, while if a lighter or smaller mop is being used it may be in one of its lower positions as shown in Figs. 1 to 3. The lever bar 30 will be moved to bring the plates into the position shown in Fig. 2. The mop to be squeezed is then inserted downwardly between plates 24 and 70 29. The operator will previously have placed member 35 on the mop stick and fastened it in the desired position. After the mop has been placed between the plates the operator will swing the mop stick to the left as shown in Figs. 1 to 3 75

and one of the projections 35b will engage bar 30 in one of the recesses 30b and said bar will be swung to the left with the mop stick. This movement swings levers 28 and the toggle formed by 5 the same and members 31 is straightened. This causes arms 26 and plate 29 to be swung toward plates 22 and 24 and the mop is squeezed between these plates. The water squeezed from the mop will pass through holes 21f and around the sides 10 of the horizontal portion of plate 22, said water thus draining back in the pail. The mop stick can then be swung to the right as shown in Figs. 1 to 3 and lever bar 30 moved to the right. The mop can then be readily removed from between 15 plates 24 and 29. The pin 32 is provided so that if excessive pressure should be exerted on the mop said pin will be broken and there will be no damage to the mop or apparatus. Pin 32 can be placed in different sets of the holes 30a so that 20 different breaking pressures may be had.

In the operation of the structure shown in Figs. 8 to 10 and 17 and 18 the plate 43 will be adjusted according to the weight or size of the mop. If the mop is a heavy or large one said plate will 25 be placed in its lowest position. In this structure the plates are held in separated position by springs 47. The operator places the mop downwardly between plates 40 and 42 and then swings the mop stick to the left as shown in Fig. 8. The 30 mop stick engages in material 53 in bar 52 and bar 50 together with levers 28 are swung to the left. This straightens the toggle and plate 42 is moved toward plate 40 so that the mop is squeezed between said plates. The water can drain 35 through slots 43c as well as through slots 40a. When the pressure is relieved on the mop stick springs 47 will separate the plates and the mop can be removed.

In Figs. 11 to 16 a pail 20 is shown and a frame 40 member 55 is illustrated having side plates 55a with slots 55b therein forming tongues or hooks 55c. The side members 55a can thus be disposed on the side or partition 20a, the latter extending into slots 55b and the tongues 55c being disposed 45 at one side of said side or partition while the main portion of side plates 55a have their edges extending along the other side of said side or partition. Plates 55a are shown as having a projecting portion 55d at their lower ends engaging 50 said side or partition 20a. Side plates 55a have holes 55f extending therethrough. Frame 55 has a portion 55e of plate-like form, extending between side plates 55a, which side plates extend in parallel relation adjacent the sides of the pail 55. Plate 55e extends downwardly into pail 20 extending outwardly at a greater angle adjacent its upper end and at its lower portion extending substantially horizontally and to a point slightly 60 beyond the plane of the vertical edges of side portions 55a. The side plates 55a adjacent one upper corner have a plurality of holes 55g therethrough and small headed and nutted bolts 55 are provided adapted to extend therethrough and through one end of a pair of links 57. The 65 other ends of links 57 are pivotally connected by rivet pivots 58 to the ends of bars 59, having their lower ends extending in parallel relation and other portions 59a converging and then extending in parallel relation along opposite sides respectively of a bar 60 extending above the frame 70 55. The parallel portions 59a have elongated slots 59b formed therein, and headed and nutted bolts 61 pass respectively through these slots and through the bar 60. The parallel parts of the 75 portions 59a are of angular formation as shown

in Figs. 13 and 16 and have riveted thereto a plate 62. Plate 62 as shown has ribs 62a struck up therein and this plate extends substantially to the lower parallel portions of bars 59. A plate 63 is provided, extending between side plates 55a, 5 which plate has secured thereto bars 64 extending along the inner sides of side plates 55a and pivoted thereto respectively by the rivets or bolt pivots 65. Bars 64 extend slightly above the top of plate 63 and are pivoted at their upper ends 10 to the outer sides of the lower parallel portions of bars 59 by the rivets or bolts 66. The bar 60 extends upwardly above the tops of bars 59 and plate 62 and is then offset and has secured there-to a block 67 by the rivets 67a. Block 67 has a 15 concave groove in the side adjacent plate 62 and is preferably covered with a layer 69 of some soft or yielding material such as leather. As shown in Fig. 14, the side of block 67 adjacent bar 60 is formed on a convex curve about a horizontal axis. 20 It will be noted that the upper end of bar 60 is bent at right angles as shown in Figs. 11 and 12, as well as being offset laterally. A compression coil spring 68 surrounds bar 60, bearing at one end against the out-turned portion of bar 60 and 25 at its other end against the top of plate 62. This spring normally holds bar 60 in position with the nuts 61 substantially midway of the slots 59b.

In operation, when the mop is to be squeezed, it is placed between the plates 63 and 55e in the 30 position which they occupy in Fig. 11. The operator then places the mop stick 42 in the groove in the block 67 as indicated in dotted lines in Figs. 11 to 14 and swings the mop stick to the left as shown in Fig. 11. This movement swings 35 plate 63 about the pivot 65 and said plate approaches plate 55e. The mop is squeezed between these plates and the water therefrom runs downward under plate 63 into the pail as well as through the holes 55f into the pail. It will be 40 noted that as the mop stick 42 and bar 60 are swung to the left, the lower portions of bars 59 and the links 57 act to form a toggle which is being straightened. There is an increasing leverage, therefore, on the plate 63 as it approaches 45 plate 55e. After the mop is thus squeezed between plates 63 and 55e, the operator can swing the mop stick again to the right and quickly move the same from engagement with block 67. The mop stick 42 is held in proper engagement with 50 the block 67 and need engage only a small portion of the surface of the soft or yielding member 69. Said member 67 can move vertically upwardly or downwardly within the limit of travel of plate 61 in the slots 59b. Should it be moved 55 downwardly, it will be returned to normal position by the spring 68 and if moved upwardly, will return to normal position by gravity. It will be noted that the increased angle of the flare on plate 55e accommodates the movement of the 60 mop as the plates come to mop squeezing position.

From the above description it is seen that applicant has provided a simple and yet very efficient structure of mop squeezing apparatus. It 65 will be seen that the pressure on the mop increases as the mop stick is swung to the left as described. An easy and convenient arrangement is had for exerting the desired pressure on the mop. It will also be seen that by moving member 35 that more or less leverage is obtained in 70 moving or swinging bar 30. The apparatus is adapted to be removably supported in a pail as shown, or it may be permanently secured in a pail. The parts are comparatively few in number and can be strongly and ruggedly made. It is 75

obvious that the device will have a high degree of utility for the purpose intended.

This application is a division of applicant's co-pending application S. N. 657,956, filed February 23, 1933, which has matured into Patent No. 2,049,619.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

15. What is claimed is:—

1. A mop squeezing apparatus having in combination, a frame, a pair of plates mounted therein for relative swinging movement toward and from each other, a toggle lever connected to said frame and to one of said plates for moving said latter plate including an upwardly extending lever arm swingable in the same direction as said latter plate and means for varying the point of connection of said toggle lever with said frame for varying the relative positions of said plates in separated position.

2. A mop wringer having in combination, a frame, a plate pivotally mounted in said frame for swinging movement therein, a second plate toward which said first mentioned plate is movable, said plates diverging upwardly when in separated condition, a lever arm pivotally connected to said first mentioned plate, a member pivotally connected to one end of said lever arm and frame forming a toggle with said lever, a link having one end pivoted to said lever and its opposite end pivoted to said frame below said plates, said second plate being secured to said link, said lever arm extending upwardly beyond said first mentioned plate and having means thereon engageable by the stick of a mop for swinging said lever arm to straighten said toggle and cause approaching movement of said plates.

3. A mop wringer having in combination, a frame, a stationary plate carried thereby, a second plate swingable toward and from said first mentioned plate, a link rigid with said second plate and swingable therewith about a fixed axis below said plates, a second link pivoted at one end to said frame, a lever pivoted at one end to said first mentioned link to form therewith a toggle lever, said first mentioned link being pivotally connected intermediate the ends of said lever and means for swinging said lever about its connection to said first mentioned link to straighten said toggle and move said plates together to squeeze a mop therebetween.

4. A mop wringer having in combination, a frame, a stationary plate carried thereby, a second plate swingable toward and from said first mentioned plate, a link pivoted at one end to said frame, a lever pivoted at one end to the other end of said link to form therewith a toggle lever, a link to which said swingable plate is secured swingable about an axis below said plates and pivotally connected at its upper end to an intermediate point on said lever, means for swinging said lever to straighten said toggle and move said plates together to squeeze a mop therebetween and means for connecting said first mentioned link at different points on said frame to vary the straightened position of said toggle lever and the distance between said plates when in mop squeezing position.

75. 5. A mop wringer having in combination, a

mop, a stick therefor, a frame adapted to be supported in a pail and having side portions, a plate pivotally mounted on said side portions and extending substantially the distance therebetween, a second plate mounted in said frame and facing said first mentioned plate, a member extending upwardly from said first mentioned plate having a recess therein and a member carried by the stick of the mop having a portion receivable in said recess to swing said member and said first mentioned plate and means for holding said member in different positions longitudinally of said handle.

6. A mop wringer having in combination, a frame adapted to be supported in a pail and having side portions, a plate pivotally mounted on said side portions and extending substantially the distance therebetween, a second plate mounted in said frame and facing said first mentioned plate, a member extending upwardly from said first mentioned plate having a plurality of spaced recesses therein and a member carried by the stick of a mop to be squeezed having a portion receivable in one of said recesses to swing said member and said first mentioned plate.

7. A mop wringer having in combination, a frame, a plate pivotally mounted in said frame for swinging movement therein, a second plate toward which said first mentioned plate is movable having an opening between its top and bottom, said plates diverging upwardly when in separated condition, means for swinging said first mentioned plate toward and from said second plate and a bottom plate carried by one of said plates and movable through said opening as said plates approach each other.

8. The structure set forth in claim 7 and means for securing said bottom plate at different positions on the plate by which it is carried.

9. A mop wringer having in combination, a frame, a plate pivotally mounted in said frame for swinging movement therein, a second plate toward which said plate is movable, said plates diverging upwardly when in separated condition, said second plate having a movable portion and means for holding said portion in different positions to vary the position of the upper edge of said plate.

10. A mop wringer having in combination, a frame, a plate pivotally mounted in said frame for swinging movement therein, a second plate toward which said plate is movable, said plates diverging upwardly when in separated condition, a lever for swinging said first mentioned plate, an arm extending upwardly from said lever having means adapted to be engaged by the stick of a mop to be squeezed and a connection between said lever and arm including a frangible member adapted to be broken if excess pressure is applied.

11. A mop wringer having in combination, a frame, a plate pivotally mounted in said frame for swinging movement therein, a second plate toward which said first mentioned plate is movable and having a slot extending thereacross between its top and bottom edges, said plates diverging upwardly when in separated position and a bottom plate carried by said first mentioned plate and movable through said slot in said second plate in the relative movement of said plates.

12. The structure set forth in claim 11, said bottom plate having spaced lugs projecting through apertures in said first mentioned plate and a removable member having portions ex-

tending through apertures in said lugs to hold said bottom plate in position.

13. A mop wringer having in combination, a pair of plates mounted for relative swinging movement toward and from each other to and from mop squeezing position respectively, a bottom plate between said plates disposed substantially horizontally and means for varying the distance between said bottom plate and the top edge 10 of one of said first mentioned plates.

14. A mop wringer having in combination, a frame, a plate pivotally mounted in said frame for swinging movement therein, a second plate toward which said first mentioned plate is movable, said plates diverging upwardly when in separated condition, a bottom plate carried by one of said plates and extending substantially horizontally therebetween and means for varying the distance between said bottom plate and 20 the top edge of said second plate.

15. A mop wringer having in combination, a frame, a plate pivotally mounted in said frame for swinging movement therein, a second plate toward which said first mentioned plate is movable, said plates diverging upwardly when in separated condition, a lever fulcrumed on said first mentioned plate and extending below said fulcrum and means pivoted to the lower end of said lever and to said frame and forming with 30 said lever a toggle, said lever being movable with said plate whereby swinging of said lever will straighten said toggle and cause said plates to approach.

16. A mop wringer having in combination, a frame, a plate pivotally mounted in said frame for swinging movement therein, a second plate toward which said first mentioned plate is movable, said plates diverging upwardly when in separated condition, a lever fulcrumed on said first mentioned plate and having its end below its fulcrum, a link pivoted at one end to the lower end of said lever and at its other end to said frame and forming with said lever a toggle, whereby swinging of said lever will straighten 45 said toggle and cause said plates to approach.

17. A mop wringer having in combination, a frame, a plate pivotally mounted in said frame for swinging movement therein, a second plate toward which said first mentioned plate is movable, said plates diverging upwardly when in separated condition, a lever in the form of a fork having ends pivoted to said first mentioned plate, means connected to said lever and frame for moving said first mentioned plate upon swinging 55 of said lever, said first mentioned plate moving through said fork as said lever is swung from one position to the other.

18. A mop wringer having in combination, a frame, a plate pivotally mounted in said frame for swinging movement therein, a second plate toward which said first mentioned plate is movable, said plates diverging upwardly when in separated condition and means for varying the distance between the upper edges of said plates 65 when in separated condition.

19. A mop wringer having in combination, a frame adapted to be supported in a pail and having side portions, a plate pivotally mounted on said side portions and extending substantially 70 the distance therebetween, a second plate mounted in said frame and facing said first mentioned plate, a member extending upwardly from said first mentioned plate, a member carried by the stick of a mop, said last mentioned members being constructed and arranged to be mechanically 75

connected to swing said first mentioned plate and being readily detachable.

20. A mop wringer having in combination, a frame, a plate pivotally mounted in said frame for swinging movement therein, a second plate 5 toward which said first mentioned plate is movable, said plates diverging upwardly when in separated condition and a bottom plate extending substantially horizontally between said plates some distance from the top thereof and being 10 readily removable.

21. A mop wringer having in combination, a frame, a plate pivotally mounted in said frame for swinging movement therein, a second plate toward which said first mentioned plate is movable, said plates diverging upwardly when in 15 separated condition and a bottom plate extending between said plates some distance from the top thereof and being removably connected to one of said plates. 20

22. A mop wringer having in combination, a frame, a plate pivotally mounted in said frame for swinging movement therein, a second plate toward which said first mentioned plate is movable, said plates diverging upwardly when in 25 separated condition and a bottom plate extending between said plates and connected to one of said plates for swinging movement relatively thereto.

23. A mop wringer having in combination, a frame, a plate pivotally mounted in said frame for swinging movement therein, a second plate toward which said first mentioned plate is movable, said plates diverging upwardly when in separated condition, a lever arm fulcrumed on said 30 first mentioned plate and bodily movable therewith about the pivotal point of said first mentioned plate, a link pivotally connected at its ends respectively to said lever arm and to said frame forming a toggle with said lever arm which 40 toggle is straightened to cause said plates to approach and is straightened by swinging said lever arm.

24. A mop wringer having in combination, a frame, a plate pivotally mounted in said frame 45 for swinging movement therein, a second plate toward which said first mentioned plate is movable, said plates diverging upwardly when in separated condition, a lever arm pivotally connected adjacent one end to said first mentioned 50 plate adjacent the upper end thereof and extending upwardly above said plate, a link connected by a pivot to the lower end of said lever arm, said link being connected at its other end by a pivot to said frame at the side of said movable plate 55 remote from said second plate, one of said latter mentioned pivots being adjustable as to position to vary the distance between said plates when in separated condition.

25. A mop wringer having in combination, a frame, a plate pivotally mounted in said frame for swinging movement therein, a second plate toward which said first mentioned plate is movable, said plates diverging upwardly when in separated condition, a lever fulcrumed on said first 65 mentioned plate at the upper portion thereof, a link having its ends pivotally connected to said lever and frame respectively forming a toggle with said lever and means for varying the position of a pivot of said toggle to vary the distance 70 between the fulcrum point of said lever and said second plate.

26. A mop wringer having in combination, a frame, a plate pivotally mounted in said frame for swinging movement therein, a second plate 75

toward which said first mentioned plate is movable, said plates diverging upwardly when in separated condition, a lever constructed and arranged to swing said first mentioned plate, said first mentioned plate having an upper portion pivoted to the lower portion thereof about a horizontal axis and swingable toward said second plate relatively to said lower portion.

27. The structure set forth in claim 26, said lever being pivoted to said first mentioned plate about the same axis about which said upper portion is pivoted.

28. A mop wringer having in combination, a

frame, a plate pivotally mounted in said frame for swinging movement therein, a second plate toward which said first mentioned plate is movable, said plates diverging upwardly when in separated condition, means for swinging said first mentioned plate toward said second plate, said second plate having an upper portion inclined upwardly away from said first mentioned plate, and said first mentioned plate having a portion swingable relatively thereto toward said upper portion of said second plate.

EDWARD PAVEK.
